Primary Examiner — Natasha Vujcic*Assistant Examiner* — Robert B Rieker(74) *Attorney, Agent, or Firm* — Stinson LLP**CLAIM**

The ornamental design for a luminaire, as shown and described.

DESCRIPTION

FIG. 1 is a perspective of a luminaire;
 FIG. 2 is a front elevational view of the luminaire;
 FIG. 3 is a top plan view of the luminaire;
 FIG. 4 is a rear elevational view of the luminaire;
 FIG. 5 is a bottom plan view of the luminaire;
 FIG. 6 is a right elevational view of the luminaire; and,
 FIG. 7 is a left elevational view of the luminaire.
 The broken lines in the drawings illustrate portions of the luminaire which form no part of the claimed design.

1 Claim, 6 Drawing Sheets(56)
